(57) **CLAIM**

The ornamental design for a user interface module for electromedical apparatus, as shown and described.

DESCRIPTION

FIG. 1 is a front elevational view of a user interface module for electromedical apparatus;

FIG. 2 is a rear elevational view of the user interface module for electromedical apparatus of FIG. 1;

FIG. 3 is a top plan view of the user interface module for electromedical apparatus of FIG. 1;

FIG. 4 is a bottom plan view of the user interface module for electromedical apparatus of FIG. 1;

FIG. 5 is a right side elevational view of the user interface module for electromedical apparatus of FIG. 1;

FIG. 6 is a left side elevational view of the user interface module for electromedical apparatus of FIG. 1; and,

FIG. 7 is a perspective view from a direction between the front and right side of the user interface module for electromedical apparatus of FIG. 1.

The broken lines shown in the figures represent portions of the user interface module for electromedical apparatus that form no part of the claimed design.
